UNITED STATES PATENT OFFICE.

THOMAS ASH AND AUGUSTUS J. FRAME, OF COLUMBUS, OHIO.

FILM-REEL.

1,393,420.

Specification of Letters Patent. Patented Oct. 11, 1921.

Application filed January 5, 1921. Serial No. 435,090.

To all whom it may concern:

Be it known that we, THOMAS ASH and AUGUSTUS J. FRAME, citizens of the United States, residing at Columbus, in the county of Franklin and State of Ohio, have invented certain new and useful Improvements in Film-Reels, of which the following is a specification.

This invention relates to improvements in film reels, and has specific reference to a new and improved structure for effecting a substantial connection between the inner end of the film ribbon and the hub structure of the reel, whereby upon the rotation of the reel, the said film will be wound or unwound with respect to the reel.

Another object of the invention resides in the provision of an attaching or clamping structure of the character stated which will be, first convenient and simple to operate, second, effective and positive in its function of clamping the end of the film to the reel, and finally to enable the structure to be readily employed in conjunction with reels of conventional design and to be produced at a relatively low cost.

A further object of the invention resides in forming the attaching or clamping structure so that the latter may be readily removed from its operating position in the event of injury, wear, replacement or damage thereto.

With these and other objects in view, as will appear as the description proceeds, the invention accordingly consists in the novel features of construction, combinations of elements and arrangements of parts, herein-after to be fully described and to have the scope thereof pointed out in the appended claims.

In the accompanying drawing, forming a part of this specification and in which similar characters of reference denote like and corresponding parts throughout the several views thereof:

Figure 1 is a view in side elevation disclosing a film reel constructed in accordance with the features of the invention, parts thereof being shown in vertical section to disclose underlying structure.

Fig. 2 is an enlarged vertical transverse sectional view taken on the plane disclosed by the line 2-2 of Fig. 1, and

Fig. 3 is a detail perspective view of the clamping spring, removed from the reel.

Referring more particularly to the details

of the invention, the numeral 1 designates a standard conventional form of film reel in its entirety. It is customary in reels of this character, the same is formed to include 60 spaced vertically disposed heads 2, which are adapted to be secured together in spaced relation by the provision of a hub structure 3, the latter being formed from sheet metal and has its circumferential edges provided, 65 as usual, with outwardly extending integral lugs 4, which are adapted to pass through registering openings provided in the sides of the heads 2, whereby upon bending the lugs 4 in lateral directions a secure and substantial connection will be provided therebetween and the hub structure 3. Also, the reel includes the usual axially disposed sleeve 5, which is adapted to be received upon a usual spindle or arbor for the purpose of effecting the rotatable support of the reel in conjunction with a suitable projecting or motion picture machine.

The present invention concerns itself more particularly with the provision of an improved film clamping structure 6, which operates to removably secure and to frictionally hold the end of a ribbon of film 7 in connection with the hub structure and to permit such film to be wound about the hub 85 structure between the heads 2 of the reel or conversely, to be unwound from the reel. In order to permit this object to be readily accomplished with maximum ease and facility and yet to provide a structure which 90 will securely hold the end of the film, the structure 6 consists of a pair of leaf springs 8. These springs are formed to include relatively flat horizontally extending tongues 9, which extend in parallelism with the longitudinal axis of the hub structure, and are formed to include, at certain of the ends thereof, laterally directed vertical portions 10, which extend through slits 11 provided in the heads 2 and lie adjacent to and in 100 parallelism with the outer walls of the heads. These vertically extending portions of the springs are secured by forming the heads with integral lugs 12, which are adapted to receive the portions 10, as shown in Fig. 1, 105 and prevent displacement of the springs. The opposite ends of the springs project through substantially rectangular openings 13 also formed in the heads 2 contiguous to the outer periphery of the hub structure 3, and the free ends of the springs 8 project through the openings 13 in order that they

may be manually engaged by the thumb of the operator. Therefore, by engaging the free ends of the springs exteriorly of the heads 2, the tongues 9 thereof may be elevated against the normal pressures exercised by the springs, thus enabling the end of a reel to be inserted between any one of the tongues 9 and the hub structure. Upon the release of the free end of the particular spring operated, the tongue portion 9 thereof will be pressed downwardly, by the inherent resiliency of the spring, into frictional engagement with the film associated therewith, and causing the latter to be pressed securely against the outer wall of the hub structure 3 and thus frictionally connected with the reel as a whole. To effect the release of the film, the free end of the clamping spring is forced outwardly away from the hub structure, this relieves pressure on the end of the film and enables the latter to be readily withdrawn from connection with the reel.

From the foregoing description, taken in conjunction with the accompanying drawing, it will be apparent that the present invention provides a clamping appliance of an unusually simple yet effective nature for the particular purpose specified. The construction is such that in the event of injury to any of the springs 8, the injured member may be readily removed by spreading the lugs 12, which permits the injured member to be withdrawn and a new spring substituted therefor. Another important feature in the invention resides in the fact that the spring is normally exteriorly operated. That is, the free ends of the springs project through the openings 13 and are therefore susceptible to exterior operation. This avoids the necessity of reaching between the restricted space existing between the heads 2, and enables the free end of a film to be attached or released within the short space of time and in a positive and convenient manner.

What is claimed is:

1. In a film supporting reel, a hub including a smooth cylindrical surface having the ends thereof connected with spaced vertically disposed heads, a spring tongue sit-

uated to resiliently engage with the outer periphery of said hub and extending in parallelism with the longitudinal axis thereof, said spring being disposed to extend substantially throughout the length of the hub, an integral outwardly and radially extending finger formed with one end of said tongue, said finger being disposed to engage with the outer face of one of said heads, means provided upon said head for securing said finger in connection therewith, and the other of said heads, contiguous to said hub structure, being provided with an opening through which the free end of said tongue is situated to project, whereby the tongue may be exteriorly manipulated to govern the clamping relationship existing between said tongue and the periphery of the hub.

2. In a film reel, a clamping appliance comprising a hub structure and spaced vertically disposed heads, a spring tongue situated to resiliently engage the outer periphery of said hub structure extending in parallelism with the longitudinal axis thereof and lying between said heads, the free end of said tongue being arranged to project through an opening provided in one of said heads, whereby said tongue may be exteriorly manipulated, and means for connecting the opposite end of said tongue securely to the rim.

3. A film reel clamping appliance comprising a hub structure having spaced vertically disposed heads secured to the ends thereof, a leaf spring disposed to extend between said heads and normally disposed in engagement with the outer periphery of the hub structure, a laterally offset end formed upon said spring, lugs carried by one of said heads and arranged to receive the offset portion of said spring, and the free end of said spring being disposed to lie in contiguity with an opening provided in the other of said heads and capable of being exteriorly manipulated to withdraw the spring substantially from engagement with the hub structure.

In testimony whereof we affix our signatures.

THOMAS ASH.
AUGUSTUS J. FRAME.
